CONTAINER AND CLOSURE THEREFOR

John R. Meggy, Elizabeth, N. J.

Application April 20, 1940, Serial No. 330,643

3 Claims. (Cl. 221—21)

This invention relates to a container and, more particularly, to a container having a closure by means of which an opening in said container may be uncovered and covered without removing said closure therefrom.

An object of the present invention is to provide a container having a closure for a container opening which is easily adjustable in regard to the opening in the container and will remain in the adjusted position.

Another object of this invention is to provide a closure for a container opening which will at all times remain attached to the container.

A further object of this invention is to provide a container having a closure which is simple and inexpensive to construct and easy to operate.

A still further object of the present invention is to provide a container closure particularly for a tooth paste, shaving and like tube which will allow access to the contents of said tube without removing the closure therefrom.

Another object of this invention is to provide a container having a closure which will indicate by contact with the operator's hand that harmful or poisonous substances are held within said container.

Other objects of the invention will become apparent in the course of the following specification.

The above and other objects of the present invention may be realized by providing one end of the container, which container may be of metal, wood, glass or any other desired material, with an elongated head flanged on the opposite sides thereof to form a track, the elongated head having therein an opening which is in communication with the interior of the container, the opposite sides, or top, of said track having a plurality of teeth extending along the same.

A cap, preferably of a resilient material of sufficient width to cover the opening in the container head, is adapted to slidably engage the flanges on said head. The opposite sides, or top, of the cap have teeth therein adapted to enmesh with the teeth on the opposite sides, or top, of the elongated head.

The invention will appear more clearly from the following detailed description when taken in connection with the accompanying drawing, which illustrates a preferred embodiment, together with a modification thereof.

In the drawing:

Figure 1 is a perspective view of the container and closure of this invention.

Figure 2 is a vertical section of the invention taken on the line 2—2 of Figure 1.

Figure 3 is a section on the line 3—3 of Figure 2, and

5 Figure 4 is a perspective view of the modification of this invention.

Like numerals refer to like parts throughout the several views.

Referring to the drawing, the reference numeral 10 designates the body portion of a container which may be of metal, wood, glass, or any other desired material, having an elongated head 11, said head having flanges 12 and 13 on the opposite sides thereof, which form a track for a

15 slidable closure.

The elongated head 11 has stops 15 and 15a on opposite ends thereof to limit the longitudinal movement of the cap. The head 11 also has an opening 16 which is in communication with the

20 interior of the container.

The head 11 may be formed on the container by molding, pressing or any other desired method.

The opposite sides of the elongated head 11 have a plurality of spaced teeth 17 therein.

25 The cap 14, which is preferably of a light spring metal, is U-shaped, the opposite sides 18 and 19 thereof slidably engaging the opposite sides 12 and 13, respectively, of the elongated head 11. The top 20 of the cap slidably engages the top surface of the head 11, the top of the cap being of sufficient width to cover the opening 16. The top 20 is knurled at 21, so that the operator's finger or thumb will not slide in respect thereto.

30 The opposite sides 18 and 19 of the cap 14 have a plurality of spaced teeth 22 adapted to enmesh with the teeth 17 on the opposite sides of the head 11. The ends 23 and 24 of the opposite sides 18 and 19, respectively, are bent to engage

35 the under side of the flanges 18 and 19, respectively, so that the cap 20 will not fall from the head 11 and to hold the top of the cap 14 firmly against the top of the head 11.

In the embodiment of the invention shown in

45 Figure 4 of the drawing, the head 11 has parallel shoulders along the opposite sides and ends thereof formed by a slight depression 25 in the top surface of the head. Orifices 26 and 27 are formed in the opposite ends of the heads, so

50 that liquid may be easily poured from the container. The cap 28 has a plurality of spaced teeth 29 on the opposite sides thereof which enmesh with the spaced teeth 17 of the head 11.

The top 30 of said cap is adapted to slidably engage the top surface of the head 11. Grooves 31

and 32 formed on the opposite side of the cap 28 engage the parallel side shoulders on the head 11. A plurality of sharp pin points 33 are formed in the top of the cap, so that, when the user touches the cap to operate the same, he will be warned that the container has therein a poisonous or dangerous substance.

The container closure of this invention is of simple construction, since the elongated head 11 may be formed therein by molding, pressing, or any other desired means, it being merely necessary to place the U-shaped cap 14, which is preferably of a light spring metal, thereon and pressing it downwardly, the cap snapping into position in relation to the head 11.

In the operation of this invention, it is merely necessary for the operator to slide the cap so as to uncover the opening 16, which is in communication with the interior of the container. While the substance is being poured or pressed from the container, the cap will remain in the position to which it was slid by the operator, since the teeth 17 which enmesh with the teeth 22 in the cap 14 will lock the same in the desired position. The amount of substance emitted from the container may be controlled by adjusting the size of the opening 16.

The teeth 17 enmeshing with the teeth 22 on the cap will also lock the cap in position over the opening 16 when the container is being pressed or otherwise handled, preventing the contents of the container from escaping therefrom. The bending of the ends 23 and 24 to engage the under side of the flanges 12 and 13 will prevent the cap from becoming disengaged from the head 11.

The cap 28 of the embodiment of the invention, shown in Figure 4 of the drawing, is operated similarly to the cap 14. The pin points 33 in the top thereof, however, will serve to warn a person attempting to open the container that poisonous or harmful substances are contained therein.

It is apparent that the specific illustration shown has been given by way of illustration and not by way of limitation and that the structure above described is subject to a wide variation and modification without departing from the scope or intent of the invention, all of which variations and modifications are to be included within the scope of the present invention.

What is claimed is:

1. In a container, an elongated head having an opening therein communicating with the interior of said container said head being flanged on the opposite sides thereof to form a track, longitudinally extending parallel shoulders extending above the top surface of said head on the opposite sides thereof, transversely extending shoulders on the opposite ends of said head extending

60

above the top surface thereof and having pouring vents therein, a plurality of vertically extending teeth longitudinally disposed along the opposite sides of said head, and a closure of resilient material adapted to slidably engage the top surface of said head and having parallel grooves in the opposite sides thereof adapted to engage the shoulders on the opposite sides of said head, said closure having depending parallel sides the ends thereof being bent toward each other and engaging the under-side of the adjacent flange on said head said parallel sides each having a plurality of vertically extending teeth therein said teeth being adapted to enmesh with the teeth in the adjacent side of said head.

2. In a container, an elongated head having an opening therein communicating with the interior of said container said head being flanged on the opposite sides thereof to form a track, longitudinally extending parallel shoulders extending above the top surface of said head on the opposite sides thereof, transversely extending shoulders on the opposite ends of said head extending above the top surface thereof and having pouring vents therein, a plurality of vertically extending teeth longitudinally disposed along the opposite sides of said head, and a closure of resilient material having sharp points projecting outwardly from the top surface thereof of said closure being adapted to slidably engage the top surface of said head and having parallel grooves in the opposite sides thereof adapted to engage the shoulders on the opposite sides of said head, said closure having depending parallel sides the ends thereof being bent toward each other and engaging the under-side of the adjacent flange on said head said parallel sides each having a plurality of vertically extending teeth therein said teeth being adapted to enmesh with the teeth in the adjacent side of said head.

3. In a container, an elongated head having an opening therein, communicating with the interior of said container, said head being flanged on the opposite sides thereof to form a track, transversely extending shoulders on the opposite ends of said head, said shoulders extending above the top surface of the head and having pouring vents therein, a plurality of parallel teeth disposed along the opposite sides of said head, and a closure slidably engaging the top surface of said head and having parallel grooves on the opposite sides thereof engaging the shoulders on the opposite side of said head, said closure having depending parallel sides engaging the under-side of the adjacent flange on said head, each of said parallel sides having a plurality of teeth which are adapted to enmesh with the teeth in the adjacent side of said head.

JOHN R. MEGGY.
